UNITED STATES PATENT OFFICE.

WILLIAM J. NOVY, OF CHICAGO, ILLINOIS.

WAISTBAND.

Application filed December 1, 1923. Serial No. 677,953.

To all whom it may concern:

Be it known that I, WILLIAM J. NOVY, a citizen of the United States, residing at 1624 South Harding Avenue, Chicago, in the 5 county of Cook and State of Illinois, have invented certain new and useful Improvements in Waistbands, of which the following is a specification.

The present invention has to do with the 10 production of clothing and relates particularly to the manufacture of trousers and the like.

Primarily the objects of the invention are the provision of a waistband which will not 15 sag and which has a neater and more finished appearance than the conventional or custom tailored trouser band, and the saving of both material and labor.

Another object of this invention is the 20 provision of a waistband whereby the canvas or stiffening material ordinarily there applied may be eliminated; a further object is the provision of a trouser construction whereby the appearance of the inside fork 25 may be improved; additionally an object of the invention is the elimination of unsightly belt loops, if desired, and the employment of the waistband material for the purpose of forming a continuous or broken tube to receive the belt; and finally the production of 30 a waistband admitting of the use of the belt entirely within the trousers whereby the exterior portion of the trousers will always present an even top.

These and such other objects as may hereinafter appear are attained by the novel construction, combination and arrangement of the several parts of the trouser band which I employ, all of which are fully illustrated in the accompanying single sheet of drawing, hereby made a part of this specification, and in which:

Figures 1, 2 and 3, are vertical sections showing modes of forming the waistband; 45 and

Figure 4 is a fragmentary view of a pair of trousers employing the invention.

Like reference characters are used to designate similar parts in the drawing and in 50 the descriptive matter which follows.

Reference should first be had to Figure 1. The ordinal 10 designates the material or cloth from which the trouser is made and which is folded upon itself to form the inner portion 11 of the band, and then inwardly or lapped, at its edge 12, to provide

a neat finish. Secured thereto is a canvas strip 13 having a folded over edge 14 through which stitch 15 passes into the narrow folded edge 12 of material 10. Lining material 16, which may be doubled, as illustrated, is disposed intermediate strip 13 and material 10, and is attached in position by stitching 17 which passes through material 10, its inner portion 11, canvas strip 13 and lining 16, leaving intermediate strip 13 and material 10 a vertical opening admitting of the insertion of a belt in a manner to be hereafter described.

Passing to Figure 2, the construction comprises material 20 and the folded over inner band 21 integral therewith, but no turned in edge is used. Canvas strip 23 disposed between portions 20 and 21 has no turned-over edge as in Figure 1. Lining 26 is disposed 70 in substantially the same manner as in Figure 1 except that it abuts a piping 20^a used to cover the rough edges of inner band 21 and of canvas 23, stitching 27 passing through 20, 21, both sides of piping 20^a, and lining 26. The usual belt space is provided between material 20 and canvas strip 23.

Reference should now be had to Figure 3. The waistband here illustrated comprises a 75 piece 30 separate from trouser material 30^a, the back 31 of the band being formed by folding the material of 30 back upon itself and turning in the edge 32 as in Figure 1. Canvas strip 33 is secured to edge 32 at its own turned up edge 34 by stitching 35. 80 Lining 36 is disposed as described in Figure 1, stitching 37 being adapted to secure material 30 and 31, canvas 33, and lining 36 to provide a belt space as in the previously described forms of the invention.

For the insertion of a belt 18, 28, or 38, a vent or opening 19 (see Figure 4) is provided adjacent each side of the fly of the trouser. Additional openings may be made about the band, if desired.

It is quite manifest that the canvas strip 13, 23 and 33, may be eliminated for the material of the waistband, doubled over as it is, supplies the stiffness usually required about the waistband of a garment. The 105 combined thicknesses of the trouser material about the waistband gives a body considerably in excess of that obtained by one thickness of material to which a canvas strip has been attached.

As hereinabove indicated, an additional object of the invention may be the elimina-

tion of belt loops. For purposes of description the space intermediate the two thicknesses of trouser material will be called a tube. It is manifest from an examination of the 5 several figures that in any form of the invention slits for the admission of the belt should be placed adjacent the fly. In Figure 4 the slits 19 are placed upon the outside front of the trouser. These may be 10 placed upon the inside in the same relative position, thus providing a trouser support wholly invisible when in position. There is an additional advantage to placing the belt in the position last described in that 15 the belt will conform to the contour of the body while the top of the trouser maintains a relatively level and horizontal undistorted position.

In order to show the modification in the 20 construction of the trouser, additional slits designated 19^a are supplied adjacent the back seam of the garment. These are for the purpose of aiding the insertion of the belt in the tube referred to and may provide means whereby the belt will give its 25 supporting effect free from the interference occasioned by a plurality of thicknesses of material.

It is equally apparent that slits for the 30 belt may be arranged in conjunction with the several seams of the garment; also, that the number of slits either inside or outside is immaterial, and that slits may be so arranged that portions of the belt are on the 35 outside of the garment, portions on the inside, and portions within the tube.

The advantages of this construction are 40 numerous. No sagging of trousers from belt are possible and the trousers are held by a uniformly disposed friction about their entire belt circumference. A neatness of finish is obtainable, with a marked reduction of labor and of materials. Lining material is saved because the lining may be accurately cut in this type of trouser. Greater 45 adjustability of the trousers about the body is obtainable and the trousers may be effectively raised or lowered by adjustments of the belt.

50 Of course, the insertion of a belt may be omitted, but the advantages of the construction are such that there is a distinct advance in the art in saving labor, materials, busheling and alteration costs.

55 In reference to busheling and alteration costs it must be noted that great simplicity

is had in raising or lowering the position of the waistband. In order to lengthen the distance from the fork to the waistband the portion of material 11, 21 and 31 is reduced. To shorten the distance referred to a greater portion of material 10 and 20 in Figures 1 and 2 is turned over and tacked down. To accomplish this it is only necessary to rip out stitches 17 and 27 and rip the seams at the back, sides and front of the trousers. This admits of a rapid alteration of the trouser at a considerable less cost in labor and time. A skilled trouser maker is unnecessary for accomplishing 70 this very simple operation.

It is manifest from an examination of the several figures that in any form of the invention slits for the admission of the 75 belt 18 may be placed anywhere.

I claim:

1. In trouser manufacture, a waistband comprising a turned over section forming a belt tunnel and having a turned in portion extending into said tunnel, a lining strip secured to said turned in portion and extending upwardly between the outer and inner portions of the trouser material to provide one side of said belt tunnel, and lining material for such trouser comprising a strip of material folded upon itself and with its free edges extending into said tunnel, said trouser material, belt lining strip, and trouser lining being secured one to another by a single row of stitches. 90

2. The combination described in claim 1, and in which said waistband is formed from a separate strip of material stitched to the trouser material in substantially the same horizontal line as said row of 95 stitching.

3. In trouser manufacture, a belt tunnel formed of material of the trouser folded upon itself, a lining for said belt tunnel comprising a stiffening material, a trouser lining comprising a strip of material folded upon itself, and means for finishing the raw edge of said trouser material comprising piping and a single row of stitching, the several elements of the trouser herein-referred to being secured one to another by said row of stitching passing through the trouser material, the turned over portion thereof, the piping upon the raw edge thereof, the lining for said belt tunnel, and the lining for said trouser. 105

WILLIAM J. NOVY.
